UNITED STATES PATENT OFFICE

147,627

DESIGN FOR A PHONOGRAPH CABINET

Ernest F. Thomson, Tuckahoe, N. Y., assignor,
by mesne assignments, to Reconstruction
Finance Corporation, Kansas City, Mo., a cor-
poration of the United States

Application March 28, 1946, Serial No. 128,024

Term of patent 14 years

(Cl. D56—4)

To all whom it may concern:

Be it known that I, Ernest F. Thomson, a citizen of the Dominion of Canada, residing at Tuckahoe, Westchester County, New York, have invented a new, original, and ornamental Design for a Phonograph Cabinet, of which the following is a specification, reference being had to the accompanying drawings, forming part thereof.

Fig. 1 is a front elevational view of a phonograph cabinet showing my new design;

Fig. 2 is a side elevational view; and

Fig. 3 is a top plan view thereof.

I claim:
The ornamental design for a phonograph cabinet, as shown.

ERNEST F. THOMSON.
